STEEPING PRESS

Thomas F. Stacy, Piqua, Ohio, assignor to The
French Oil Mill Machinery Co., Piqua, Ohio

Application February 10, 1934, Serial No. 710,692

13 Claims. (Cl. 100—50)

This invention relates to steeping presses in which pulp sheets are soaked or steeped for a desired interval of time in a caustic solution, such as caustic soda, after which the pulp sheets are compressed by the use of a hydraulically operated platen movable lengthwise of or across the press, to expel the excess steeping solution. Such a steeping press is commonly utilized in the viscose process of making rayon and cellophane.

During the steeping operation the action of the caustic solution upon the pulp or fibrous sheets causes the generation of considerable heat which is very objectionable, particularly where the temperature of the surrounding air is high. The best results are obtained where the temperature of the pulp and caustic, during the steeping operation, are maintained approximately uniform or constant. The use of cooling coils or pipes which project into the steeping compartment of the tank are unsatisfactory for various reasons, among which may be mentioned the frequent trouble from leaks and the lack of uniformity in the cooling action in different parts of the tank and the fact that pipes or coils projecting into the reaction chamber are exposed to injury and may interfere with the operation of the platen across the tank or steeping chamber of the press.

Delivery pump; with which the platen may be operated in either direction selectively and stopped and held in any intermediate position in its possible range of travel; with which overrunning of the platen beyond any selected position may be avoided; with which the different operations of the pump to cause different movements of the platen may be controlled somewhat automatically by the movement of the platen; with which the speed of the platen may be automatically changed at different points in its travel in the same direction; with which the points in the travel of the platen at which the automatic controls are effective, may be varied to some extent; with which the platen may be stopped automatically at approximately its limits of movement in both directions if the operator should fail to set the automatic controls properly, or should be negligent in operating the manual controls; with which the travel of the platen will at all times be subject to the manual controls, even if normally operating under the automatic controls; with which the automatic controls may be rendered ineffective to effective at will and in a simple manner; and which will be relatively simple, safe, dependable, durable and inexpensive.

An object of the invention is to provide improved means for controlling the temperature of the steeping solution and pulp sheets during the steeping operation, and for keeping the pulp and steeping solution at an approximately uniform or constant temperature; with which maximum efficiency and uniformity in the cooling effect throughout the tank may be obtained; which will not be open to objections to which other types of cooling means are subject; and which will be relatively simple, durable, dependable and inexpensive.

Such steeping presses are commonly made rather long, and a material loss of time of the attendant occurs and unsatisfactory results obtained if all the operations of the press must be manually supervised and operated.

Another object of the invention is to provide improved means for controlling the operation of the platen in both directions, by which the pulp sheets may be compressed to express the excess steeping solution, and with which the squeezed sheets of pulp may also, if desired, be ejected from the tank at the conclusion of the expressing operation.

A further object of the invention is to provide improved means for regulating the operations of the platen, by utilizing a reversible, variable

A further object of the invention is to provide improved means for operating a platen, with which the speed of the platen in travelling in a given direction may be varied without stopping the travel of the platen; with which the speed of travel of the platen in a given direction may be changed at selected intervals in accordance with the predetermined plan; with which the points at which the speed changes and the extent and character of the change in the travel in a given direction may be varied at will; with which the position of the platen may be accurately fixed during the drainage operation and automatically held in this fixed position; and with which the speed of travel of the platen may be progressively decreased at intervals in the path of travel of the platen.

Various other objects and advantages will be apparent from the following description of one embodiment of the invention, and the novel features of the invention will be particularly pointed out hereinafter in connection with the appended claims.

In the accompanying drawings: 50

Fig. 18 is a fragmentary side elevation of a part 65 of the control mechanism, showing the parts in a different position to that illustrated in Figs. 16 and 17;

Fig. 19 is a similar view showing the latch device in position for engaging and shifting the 70 control rod during a retractive movement of the platen;

Fig. 20 is a fragmentary transverse vertical section of said control means taken approximately on the line 20—20, Fig. 18;

75 Fig. 21 is a plan view, partly in section of the

steeping tank showing its construction in detail, with the associated parts of the press omitted;

Fig. 22 is a fragmentary vertical section of one of the upright walls of the tank, taken on the line 22—22, Fig. 21; and

Fig. 23 is a fragmentary, horizontal section taken through the horizontal bottom wall of the tank on line 23—23, Fig. 8.

In the illustrated embodiment of the invention, the steeping press includes a steeping tank 10 which is open at the top and which is closed at one end by a movable end gate or wall 11.

The opening closed by the gate 11 corresponds approximately to the cross section of the tank, and the gate may be lifted or otherwise opened at 15 the proper time in any suitable manner such as by lifting apparatus (not shown) attached to the lugs 12 on the upper edge of the gate. Since the means for moving the end gate in itself forms no part of the present invention, and is old 20 in the art, the mechanism for operating the gate has been omitted from the disclosure for the sake of simplicity. Disposed within the tank is a platen 13 which is operable across or lengthwise of the tank toward and from the end gate 25 11. The platen 13 is attached to a piston or ram 14 which extends outwardly of the tank through a stuffing box or gland 15 provided in the vertical end wall. 15a of the tank which is at the end opposite the gate 11. The pulp sheets A to be 30 steeped are disposed on edge in the tank 10 between the platen and the end gate 11, and the tank is then filled with the steeping solution, such as caustic soda. The steeping solution may be introduced into and withdrawn from the tank 35 10 by means of inlet and outlet pipes 10a and 10b, Figs. 1, 3 and 4. The side edges of the sheets A are disposed in spaced relation to the upright, longitudinal side walls of the tank, and the lower edges of said sheets engage upon spaced ribs projecting upwardly from the bottom of the tank, (see Figs. 2, 8 and 16) thereby facilitating the free circulation of the steeping solution in the tank and intimate contact thereof with the pulp sheets.

After the sheets A have soaked or steeped for the desired time, the tank 10 is drained and the sheets then compressed by advancing the platen to a desired extent to squeeze out the excess steeping solution. The platen is then retracted or operated in a direction away from the end gate so as to relieve the pressure of the sheets on the end gate, after which the end gate is elevated or removed, whereupon the platen 13 is again advanced along the tank toward the end 55 normally closed by the end gate. In doing so, the pulp sheets A are pushed out of the tank through the end thereof, and fall by gravity into a suitable receptacle or conveyor, (not shown).

The pulp sheets A are separated at frequent 60 intervals by separating or drainage plates 16 which are apertured, and at alternate intervals the plates may be double plates having drainage grooves therein. One of these drainage plates is shown in broken lines in Fig. 8. The 65 drainage plates are supported in the tank 10 in a vertical position and guided endwise of the tank by lugs 16a on opposite edges of the plates which slide in channel guides 17 which are supported on the inside faces of the side walls of 70 the tank and extend lengthwise of the tank. Extension channels 17a, Figs. 2 and 3, are arranged to move into and extend beyond the open end of the tank that is normally closed by the gate 11, when the gate is opened, so that as the platen 75

5 pushes the pulp sheets, with the interposed plates 16, outwardly through the end of the tank, the plates will be guided outwardly by the extension channels and held against descent with 10 the pulp sheets, the pulp sheets falling by gravity from between the drainage plates 16.

After this operation, the platen 14 is returned to its retracted position shown in Fig. 2 of the drawings, the plates 16 returned to the tank and 15 other pulp sheets A disposed between the plates. The gate is then closed, the steeping solution returned to the tank, and a new steeping operation 20 may then proceed.

The piston or ram 14 extends into a single 15 action cylinder 18, Figs. 1, 3 and 4. A source of actuating fluid, such as oil, is contained in a tank 19 which is preferably mounted above the cylinder 18 in any suitable manner. A pump 20 of the well known, reversible flow, variable delivery type is mounted upon the tank 19, and is continuously driven by any suitable source of power, such as by a motor 21 which is directly coupled thereto. The delivery of the pump is reversed by endwise movement of a control rod 25 or member 22, which, when moved endwise in one direction causes the pump to deliver operating fluid to an outlet pipe 23, and when moved in the opposite direction, causes the pump to deliver the operating fluid to another pipe 24. 30 When the control rod or member 22 is in an intermediate position, the pump is set for neutral delivery, that is, it operates without delivery of any fluid in either direction.

The pipe 23 is connected to a pair of single 35 action pull-back cylinders 25 and the pipe 24 is connected to the main ram cylinder 18, the pipe 23 being divided or forked so as to transmit fluid simultaneously to both pull-back cylinders 25. The pipes 23 and 24 are also connected through 40 suitable pressure release valves 26 and 27 respectively, to a common delivery pipe 28 which opens into the tank 19. The pipes 23 and 24 are further connected to opposite ends of a differential or outwardly opening double check valve 45 29, and this check valve is in turn connected by a pipe 30 to the lower part of the tank 19.

This arrangement of the reversible flow, variable delivery pump, the tank 19 which forms a source or reservoir of operating liquid, the differential or double check valve 29, and the pipes 23 and 24 leading to the pull-back and ram cylinders 25 and 18 respectively, constitutes a hydraulic system or circuit.

As shown clearly in Figs. 1 to 8, the end of the 55 main cylinder 18 which is adjacent the tank 10 is provided with a transverse head 35, and at that end of the tank which is adjacent the movable gate 11, there is a stationary transverse head block 36 which together with said cylinder 60 head 35 is secured upon the floor or supporting surface. These parts 35 and 36 are rigidly connected at each side of the tank 10 by a pair of tie or strain rods 37. The pull-back cylinders 25 before mentioned are disposed one at each side 65 of the tank 10 between the respective pairs of tie rods 37, the opposite ends of said cylinder being slidable in the cylinder head 35 and secured in the head block 36, respectively. Each of the pull-back cylinders 25 is provided with a reciprocable piston 38, which enters the cylinder through the head block 35. These pistons 38 have their free or remote ends rigidly secured together by a cross member or yoke 40 which straddles and is guided for longitudinal reciprocatory movement upon the main cylinder 75

18. A pair of pull-back rods 41 (Fig. 2) are secured to the yoke 40 and extend horizontally in parallel relation to the pistons 38. Each of the rods 41 passes through an aperture in the head block 35 and through a gland or stuffing box in 5 the upright end wall 18a and into the tank 10, where it is secured to the platen 13.

When the variable delivery pump 20 is set to advance the platen 13, fluid under pressure passes by way of the pipe 24 into the cylinder 18 and 10 acts directly upon the ram 14 to force the ram outwardly of its cylinder. At this time, fluid under pressure is not being delivered to the pull-back cylinders 20 and 25, and since the pull-back piston 38, the yoke 40, and the pull-back rods 15 41 are connected to one another and to said platen, the pistons 38 will, of course, advance with the ram 14 and platen 13. When it is desired to retract the platen 13, the pump is set to deliver fluid under pressure to the cylinders 25 and is withdrawn from cylinder 15. This causes movement of the pistons 38 towards the left in the drawings, and through the yoke 40 and rods 41 retracts the platen 13.

The features of this invention relating to the 25 control means for the reversible flow, variable delivery pump 20 and the platen 13, except insofar as it has to do with the movement of the platen when discharging pulp sheets out of the open end of the tank described, may be used with steeping 30 tanks not provided with a removable end gate or wall, and in which the sheets after steeping, are lifted out of the open top of the tank.

In the construction shown in Figs. 1 to 14, the control rod or member 22 extends lengthwise 35 along one side of the tank 10 in parallel relation to, and directly over, the upper strain rod 37 at that side of the tank. Owing to its length and its consequent possible sagging or deflection, this rod 22 is preferably supported intermediate of its 40 ends upon rollers or anti-friction devices 42 journaled upon collars or clamps 43 secured upon said strain rod 37 and adjustable along the same.

The means for transmitting the endwise movement of the control rod or member 22 to the 45 reversible flow variable delivery pump 20 to control the delivery of the pump are illustrated in Figs. 3, 7, 13 and 14, and include a transversely extending, horizontal operating shaft 45 (Fig. 14) journaled in a bracket 46 depending from the 50 tank 19 below the pump 20, the shaft being provided at its inner end with a spur pinion 47 meshing with a spur gear 48 secured on one end of a second transverse, horizontal shaft 49. This end of shaft 49 is journaled in the bracket 46, while 55 its other end is journaled in a second bracket 50 depending from the tank 19. Intermediate of its ends, the shaft 49 is provided with a pinion 51 which meshes with a series of rack teeth 52 formed on the adjacent end of the control rod 60 22. This end of the control rod is preferably mounted in horizontal guides 53 formed, for example, on the bracket 46 and which permit horizontal, reciprocable movement of the control rod and retain the rack 52 and pinion 51 in mesh with 65 one another.

The shaft 49 is also provided with a sprocket wheel 55 (Fig. 13) connected by a sprocket chain 56 to a small sprocket wheel 57 (Figs. 3 and 7) secured to one end of a horizontal, transversely 70 extending actuating rod 60 disposed directly above the pump 20. The rod 60 has a threaded portion which extends into a correspondingly threaded sleeve 61 secured in an upwardly extending bearing 62 mounted upon the pump 20, and the end 75

of said rod 60 remote from the sprocket wheel 57 is pivoted to a lever 63 in such a manner that endwise movements of the rod 60 in one direction or another will cause the pump to be actuated in the well-known manner of reversible flow, variable delivery pumps, so as to cause delivery of fluid under pressure alternately to the pipes 23 and 24 for the purpose described.

The operating shaft 45 is preferably provided with a hand wheel 65 which upon being rotated in one direction or the other will, through the endwise movement of the actuating rod 60 effect the desired control of the pump 20.

The described mechanism constitutes a manual means for controlling the movement of the platen 13 through the pump 20, and since the control rod 22 is relatively long, owing to the length of the tank 10, a second hand control is preferably provided at the opposite end of the control rod so that the operative may actuate the latter from the end which is most convenient. This second manual control comprises a hand wheel 68 (Figs. 1 and 3) secured to the outer end of an operating shaft 69 which is operatively connected through means identical with the other manual control to actuate a pinion meshing with rack teeth on the adjacent end of the control rod.

The arrangement of the manual control mechanism is such that, assuming the pump to be in neutral delivery position and the platen 13 at rest in approximately the position shown in Fig. 2, an advance of the platen towards the right from that position may be initiated by a clockwise rotation of either of the hand wheels 65 or 68, which will cause a movement of the control rod 22 toward the left. The platen 13 may be brought to rest at any time by shifting the control rod 22 toward the right, by a rotation of either of the hand wheels in the opposite direction to an extent such as to place the control rod 60 in neutral delivery position. The continuation of the movement of either of the hand wheels in the last mentioned direction will set the pump to deliver fluid in a reverse direction, and when the platen assumes the desired retracted position, its travel may be arrested by again actuating one of the hand wheels to reset the pump 20 for neutral delivery.

In order to effect an automatic actuation of the control rod 22 for controlling the movements of the platen 13 through movements of the latter, I provide, on said rod 22, one or more stops or dogs, two such stops 72 and 73 (Figs. 1 to 12) being shown. These stops are slidably adjustable lengthwise of the rod 22, and are secured thereto in any desired position by set screws 74 with lock nuts 75. Each dog or stop extends for a short distance above the control rod and terminates in a horizontal flat face 76 forming with the transverse sides of the stops a pair of abrupt shoulders 77 and 78 (Figs. 9 and 10). The control rod 22 is also preferably and additionally provided, adjacent each end of the tank 10, with fixed stops or members 79 and 80 (Figs. 2 and 3), the purpose of which will be described presently.

Suitable means are provided whereby the stops 72 and 73 may be engaged to shift the control rod in one direction or another through movement of the platen 13. For this purpose (Figs. 1 to 14) a laterally extending arm 81 is rigidly secured to the platen 13, as shown clearly in Figs. 2, 6, and 8, and which extends outwardly over the adjacent side wall of the tank 10 and at its outer end, terminates in an abutment block 82. The lower face 83 (Figs. 9 to 12) of said block extends over the control rod 22 in a position to clear the

top faces 76 of the stops 72 and 73, and the front vertical face of said block is formed with a vertical recess 84 for the reception of a relatively movable abutment member 86, which is mounted to swing about a horizontal pivot 85 extending across said recess 84.

This abutment member 86 may assume a depending, operative position in the recess 84, as shown in Figs. 9 and 11, or it may be swung upwardly into an inoperative position, as shown in Figs. 10 and 12, about its pivot 85 through an angle of 180 degrees.

The movable abutment member 86 has transverse abrupt shoulders 88 and 89 which, when the block is in its depending operative position, 15 are disposed to engage with the shoulders 78 and 77 of the stops 72 or 73 in the advance and return movements, respectively, of the platen 13.

Upon a stud 90 extending forwardly from the front face of the depending abutment member 86, see Fig. 9, I pivot a latch member 91, having a hooked nose or end 92. The abutment member 86 is provided with an offset horizontal rest 93 (Fig. 11) which, when the member is in depending position, supports the latch 91 in operative position in which it extends in a horizontal direction along rod 22. The latch 91 also has a terminal, inclined cam face 94 which, in the pressing travel of the platen 13 and abutment member 86 towards one of the stops 72 or 73, 30 engages and rides over stop 72, and when the shoulder 88 of the abutment member engages said shoulder 78, the hook portion 92 of the latch will drop down into engagement with the opposite shoulder 77 of that stop, since the distance between the hook 92 and the shoulder 88 is equal to or slightly greater than the distance across the stop, thus latching the control rod or member 22 to the platen.

The pivot stud 90 for the latch 91 preferably extends outwardly to form a handle, see Fig. 11, by which the movable abutment member 86 and its latch 91 may be swung about the pivot 85 into the upper or inoperative position in which the latch 91 rests upon the top face of the abutment block 82, as shown in Figs. 10 and 12. In this inoperative position, these parts 86 and 91 will have no effect upon the control member 22, since they then travel above and are clear of both of the stops 72 or 73, during the travel of 50 the platen.

The operation of the control means described is as follows:—Assuming that the platen 13 is in its retracted position, shown in Fig. 3, and that the pump 20 is in neutral delivery position, then the desired number of pulp sheets A are placed in the steeping tank 10 in interposed relation to the separating plates 16, after which the steeping solution is introduced into the tank and the pulp sheets allowed to steep for the necessary length of time, after which the excess solution is drained from the tank. Next the abutment member 86 and latch 91 carried thereby are swung into their upper or inoperative positions. The next step is to advance the platen 13 towards the right, in the drawings, to a position in which it will apply the necessary pressure upon the pulp sheets to expel the excess steeping solution therefrom, during which time the solution may be withdrawn from the tank. To so advance the platen the operator, by appropriate manipulation of one of the hand wheels of the manual controls, shifts the control rod 22 towards the left, in the drawings, thereby placing the pump 20 in position to deliver fluid under 70

pressure to the cylinder 18. After the platen in its advance has moved to a position in which the abutment member 86 and its latch 91 have cleared the first stop 73 on the control rod, the 5 operative lowers the abutment 86 and its latch 91 into their lower or operative positions, and then, upon continued advance movement of the platen, the latch 91 will engage and ride over the second stop 72, its hooked end dropping into 10 position in engagement with the shoulder 77 of this stop. At the same time the shoulder 88 of the abutment member 86 will come into contact with the opposite shoulder 78 of the stop 72, thereby coupling or locking the platen and control rod together, so that in the continued advance of the platen the control rod 22 will be shifted towards the right. This movement of the rod 22 causes the setting of the pump 20 for 15 neutral delivery, through the rotation of the pinion 51 by the rack 52, and consequent rotation of the actuating rod 60.

If, for any reason, the pump control rod 60 should move past its neutral delivery position, even to a slight extent, a reversal of the direction 20 of delivery of the pump would occur, which would cause the actuation of the platen in the opposite direction, or towards the left, but since the control rod 22 is locked to the platen by the engagement of abutment member 86 and latch 25 91 with the stop 72, a corresponding movement of the control rod towards the left with the return movement of the platen would be effected, thus immediately returning the pump again to neutral delivery condition, and stopping travel 30 of the platen, before the platen has passed the position in which it should have been stopped in its forward travel. With the platen advanced to a certain substantially fixed position as determined by the stop 72, a certain pressure will be 35 built up on the pulp sheets as determined by the resistance to the forward motion of the ram. That is, the pump will build up whatever pressure is required to advance the ram to the desired point and this will in turn build up the 40 pressure on the pulp sheets. With the ram standing in a certain fixed position, however, this pressure on the pulp sheets is a constantly diminishing one because the solution is being drained out of the pulp sheets, and as it drains 45 out the bulk is naturally decreased, resulting in a drop in the pressure.

After the pressure has been held on the sheets for the necessary length of time, the abutment 50 86 and latch 91 are moved temporarily into inoperative position and the platen then retracted sufficiently to relieve the pressure on the gate 11, so that the same can be raised. This relatively 55 short retractive movement of the platen is initiated by the manipulation of one of the hand controls, and as soon as the movement starts the abutment 86 and latch 91 are returned to operative position. The retraction of the platen continues until the shoulder 89 of the abutment member 86 engages the right hand face 77 of the 60 other stop or dog 13, and through it shifts the control rod 22 towards the left to the required distance to place the pump 20 in neutral delivery condition, whereupon the retraction travel of the platen will be stopped. The position into which 65 stop 13 is adjusted and fixed, determines the stopping point in this retraction of the platen, and is just sufficient to release the pressure on the end gate of the tank and enable opening of that end gate.

70 The gate 11 is then opened, and the control

rod again actuated to the left, by operation of one of the manual controls, so as to place the pump 20 on delivery stroke to advance the platen. The platen 13 will then advance again to an extent sufficient to eject the pulp sheets 5 A and their associated separating plates 16 through the open end of the tank, where the pulp sheets will be discharged by gravity. During the sheet ejecting movement of the platen, the member 86 and latch 91 should be swung into 10 their upper or inoperative positions so as to clear the stop 72.

According to normal procedure, the platen 13 is arrested in its advanced, sheet ejecting position just described by the actuation, by the operator, of one of the hand controls 65 or 68, but in the event that this procedure is overlooked, the platen will be brought to rest automatically by the engagement of the platen block 82 with the fixed stop or part 80, before mentioned, at the right-hand end of the control rod or member 22 which will result in the pump 20 being again reset to neutral delivery condition. The provision of the stop 80 which is higher than the stops 72 and 73, so as to be engaged by the 25 block 82 regardless of the position of member 86 and latch 91, therefore, constitutes a safety device preventing the platen 13 from advancing beyond a safe extent. The same advantage is to be had when the control means described is used 30 in connection with steeping tanks which are not provided with movable end gates.

The provision of the second stop 72, which may be adjusted to any desired position to stop the platen in accordance with the desired pressure required upon the pulp sheets, which will, of course, vary with different conditions of the sheets and the number thereof, also relieves the operative of the responsibility of using his judgment as to when to stop the advance of the 40 platen. When using only visual judgment the results are certain to vary. The use of the stop, therefore, ensures greater uniformity in the results than is possible without its use.

After the pulp sheets have been ejected and 45 the platen 13 brought to rest in its advanced position, as just described, the abutment member 86 and latch 91 are left in their inoperative upper positions, and the platen 13 is then started on its travel in the opposite direction by the appropriate manipulation of the hand wheel 65 or 68 of one of the manual controls, and when the platen 13 has been retracted to the desired extent, another actuation of the hand wheel in a direction to place the pump in neutral delivery 55 condition to stop the travel of the platen is necessary. If again the operative overlooks this step and fails to actuate the pump to place it into neutral, the other fixed stop 19 near the opposite end of the tank 10 will be engaged by the abutment block 82 on the end of the arm 81 of the platen, and then the continued movement of the platen will shift the control rod 22 towards the left, in the drawing, and through it operate the actuating rod 60 in a direction to shift the pump 65 into neutral delivery condition. The stop 19 is also a safety device which prevents the building up of excessive or unsafe pressure as the platen is retracted.

During the time that the platen is idle, and 70 in fully retracted position, but with the motor 21 for the pump 20 still running, such as while the pulp sheets are being placed in the tank 10, it is desirable to provide means for preventing the accidental or unintentional actuation of the 75

control rod 22, as would be the case, for example, if some one should accidentally turn one or the other of the hand wheels of the manual controls, or in case the control rod 22 should be shifted 5 unintentionally in any other manner.

For this purpose, Fig. 15, an additional latch 100 may be carried by the platen 13, and for convenience is mounted upon the same pivot 99 as the first latch 91, but the latch 100 extends in the opposite direction to the latch 91, and at its free end is provided with a hook portion 101. It will be remembered that the platen 13 was brought to rest in its retracted position by the engagement of the abutment block 82 with the right-hand end of the stop 79, and the placing of the pump into neutral delivery condition. If, therefore, while the parts are in this position, the abutment member 86 is swung downwardly into operative position, the hook 101 of the latch 100 will extend across stop 79 and will engage with the opposite end or left-hand of said stop 79, thus positively locking the control rod 22 and the manual controls against actuation. The member 86 should, of course, be returned to its inoperative position to disconnect the latch 100 from the stop 79 or latch 100 lifted before the press is started again. The same procedure may be employed in connection with the other fixed stop 80, if desired, to lock the platen in its 25 fully advanced position. Any other suitable means may be provided for effecting these results.

In the foregoing description of the operation of the steeping press, it will be understood that the platen travels in an advancing direction from its retracted inoperative position at an approximately uniform speed, dependant upon the resistance encountered, since the pump is delivering actuating fluid at a uniform rate. This 35 speed may be relatively high, with the possible disadvantage or result that when the full pressure of the platen is suddenly applied to the pulp sheets for squeezing the excess solution therefrom, some of the pulp or steeping solution might be forcibly ejected from, or thrown 40 out of, the press, since at this time the sheets, being full of solution, are relatively soft and wet. Also, possibly due to the fact that the drainage of the solution from the sheets would occur first 45 around the exposed edges thereof, leaving them relatively dry on these edge portions, while the center remains wet, a consequent forcing of the drier edge portions of the sheets from between the separator plates might result from the sudden 50 action of the high pressure on the relatively wet pulp in the center of the sheets.

It may, therefore, be desirable at times to gradually slow down the speed of the travel of the platen during its advance stroke, so that the 55 pressure would be more gently and gradually applied to the pulp sheets during the operation of expressing the excess solution therefrom, a practical arrangement for this purpose being illustrated in Figs. 16 to 20, inclusive.

In this construction, an operating rod 122 corresponding to rod 22 of Figs. 1 to 15, carries a plurality of spaced, adjustable stops, for example, three, designated 123, 124 and 125, arranged approximately as shown in Fig. 16, and which may 60 be identical in construction with the stops 72 and 73 of the previous construction.

The arm 81 (Fig. 20) of the platen is provided, adjacent the rod 122, with a block or supporting member 126 having a vertical face 127 extending 65 parallel to the axis of the rod 122. A pivot 128,

on which is freely mounted a latch or member 129, projects horizontally from face 127. A notch or recess 130 is formed in the lower edge of latch 129 and adjacent the recess and remote from the pivot 128, the latch is provided with an inclined 5 or beveled cam face or nose 131. The latch also carries a short transverse pin 133 upon which is rotatably journalled a roller 134, and this pin projects forwardly of the roller so as to form a handle. The latch 129 is directly over the longitudinal axis of the rod 122, and it rests upon and slides lengthwise of that rod.

The operation of this control mechanism, assuming the platen to be in its retracted, inoperative position, Fig. 16, with the latch 129 resting 15 freely on the control rod 122, is as follows:—When the control rod 122 is actuated in the proper end-wise direction by one of the manual controls to start the advance movement of the platen, the latch 129, travelling with the platen, will ride 20 along the control rod 122 until the lower cam face 131 comes into engagement with the first adjustable stop 123. Continued movement of the platen will cause the cam 131 to ride over this stop until the notch 130 of the latch is disposed above and aligned with said stop 123 (Fig. 17), whereupon the latch will descend by gravity and latch itself to that stop 123 thus locking the control rod to the platen.

As shown in Fig. 16, a relatively fixed projection 30 140 with an inclined cam edge is carried at the upper end of a collar 141, that is adjustably secured to the adjacent strain rod 37 at the right of the stop 123 and in the path of travel of the 35 roller 134 on the latch 129. The coupling of the control rod 122 to the platen by means of the latch 129 will, in the continued advance of the platen, cause the rod 122 to be shifted to the right, thereby actuating the pump control 60 in such a 40 manner as to reduce somewhat the rate of delivery of the pump and hence reduce the speed of travel of the platen which, of course, if continued would ultimately result in bringing the pump to neutral delivery condition and stop the 45 travel of the platen. However, before the platen is stopped, the roller 134 of the latch 129 engages and rides upwardly along the inclined cam 140 effecting the disengagement of the latch 129 from the stop 123, see Fig. 18, and as soon as the roller passes beyond the cam 140 the latch 129 will drop 50 by gravity to its former position in sliding engagement with the control rod 122.

The platen will now continue its advance at a somewhat reduced speed, as a result of the foregoing operation. After further travel of the 55 platen, the cam 131 on the latch 129 engages with the second stop 124 of the control rod 122, whereupon the latch 129 will automatically lock itself to said stop and again couple the control rod 122 to the platen. The resulting movement 60 of rod 122 with the platen will cause a further reduction in the rate of delivery of the pump and thereby a reduction in the rate of travel of the platen in that direction. This second movement of the control rod 122, however, may also be stopped before it moves a distance sufficient to actuate the pump to neutral delivery position, since during this second increment of reduced movement, the latch 129 will operatively engage a second cam 144 similar to the cam 140, and be 65 automatically disengaged thereby from the second stop 124. The latch 129 is again released as it passes cam 144 and again rides upon the rod 122 as the platen continues its travel at the further reduced speed. The latch 129, however, 70 75

eventually engages the third stop 125 on the control rod, and by moving automatically into locking engagement therewith will thereby shift the control rod 122 still further to the right. Since there are no further cams in the path of the roller 133, the platen will continue to shift the control rod 122 toward the right until such movement causes the pump 28 to be brought to neutral or non-delivery condition, whereupon the travel 10 of the platen will be completely arrested. In this manner the full, required pressure upon the pulp sheets is applied gradually and gently, thus avoiding the possible undesirable results of a too sudden application of full pressure, yet obtaining 15 maximum speed of operation of the platen.

Since the stops 123 and 124 and the cams 140 and 144 are relatively adjustable lengthwise of the apparatus, said cams may be initially set to any desired relative distance from the adjacent 20 and related stops 123 and 124, so as to determine thereby the degree to which the travel of the platen is slowed down during each increment of movement of its travel between the stops 123 and 125, thus providing a very flexible control for the 25 speed of travel of the platen. By adjusting the positions of the stops 123, 124 and 125 along rod 122 and of the positions of the cams 140 and 144 with respect to the stops, the duration and point of beginning of each reduction in speed of travel 30 of the platen can be varied selectively, and any desired number of stops and cams may be employed to obtain the desired number of increments of speed reduction of the platen.

When the control means just described is used 35 with a tank having no movable end gate the platen may be permitted to travel without interruption to its retracted position. To permit this the latch 129 may be shifted by the handle 132 to an intermediate vertical position, as shown in 40 broken lines in Fig. 19 where it is releasably held by means of a spring pressed pin 148, which yieldingly engages in a recess or depression 147 on the rear face of the latch. In this vertical position, the latch will travel clear of the stops 45 123, 124 and 125 and of cams 140 and 141.

If, however, the press is provided with a movable end gate, the platen should be retracted sufficiently to relieve the pressure on said gate, to enable it to be opened for discharge of the pulp 50 sheets A. For this purpose the latch 129 may be swung through an angle of approximately 180° by means of the handle 133, from the position shown in Figs. 16 and 18, to the position in Fig. 19, in which it extends towards the left from 55 its pivot. In this position of the latch 129, an abrupt shoulder 145 thereof will slidably engage the control rod 122. The notch 138 will, of course, now face upwardly or away from the stops 123 and 124, and the roller 134 will be held in a 60 position such that it will entirely clear the cams 140 and 144 in the movements of the platen. One of the manual controls can now be actuated to start the platen in the return direction and its travel will be arrested at an intermediate position 65 by the engagement of the shoulder 145 of the latch with the first stop 123, 124 or 125 it engages such as the stop 124, for example, which, of course, will shift the control rod to the left in Fig. 19, until the pump 28 is set to neutral delivery condition and the platen travel stopped.

If it is desired to interrupt the travel of the platen at any other intermediate point, the latch may be dropped to the position shown in Fig. 19, after it has passed those stops on rod 122 which 70 one desires to be ineffective, thereby permitting

engagement of the latch with any stop, such as the stop 123. After the platen has been thus retracted to an intermediate position and automatically or manually stopped and the end gate opened, the platen can then be advanced again 5 by actuation of a manual control, to eject the pulp sheets, and may then be fully retracted to open position, for refilling the press.

Preferably the control rod 122 is provided with fixed stops 148 and 149 similar to the stops 79 10 and 80 of the first construction, and with which the block 126 on the end of the platen arm is engageable, to stop the platen at approximately the limits of its stroke, in the event that the manual controls are not actuated to stop the 15 travel of the platen.

One practical disclosure of means heretofore alluded to for controlling the temperature of the steeping solution and pulp sheets during the steeping operation in the tank 10, is illustrated in 20 detail in Figs. 8, and 21 to 23. In this construction, the steeping tank 10 has its opposite upright side walls 150 and its horizontal bottom wall 152, of hollow construction. In other words, each of the upright walls 150 comprises inner and outer 25 plates 154 and 155 respectively, arranged in spaced parallel relation, while the bottom wall 152 is similarly formed of spaced inner and outer parallel plates 157 and 158. Said walls 150 are closed at their upper edges and at the ends, thereby providing a continuous narrow transverse 30 chamber or passage from the top of one of the side walls 150 downwardly through that wall across the bottom wall 152 and upwardly to the top of the other side wall. A jacketed tank wall 35 is thus provided into which cooling liquid such as brine or ice water may be introduced, preferably under continuous flowing conditions so as to thereby absorb heat generated in the tank.

Preferably, in order to facilitate a relatively 40 rapid introduction of the cooling liquid into the jacketed walls of the tank, and to render a rapid and uniform exchange of heat between the contents of the tank and the cooling fluid, the space or chamber between the inner and outer sections 45 of the walls is divided transversely into a plurality of separate compartments. For example, three compartments 160, 161 and 162 are shown, which are separated by solid transverse walls or partitions 163 and 164, which, if desired, may be 50 formed integrally with the walls of the tank. As shown in the drawings, each compartment 160—162 is provided with separate inlet and outlet pipes 165 and 166 for the introduction and 55 discharge of the cooling liquid, said pipes preferably being extended into one of the upright walls 150 near the upper edge thereof, as shown in Fig. 8. In order to effect a thorough and uniform contact of the cooling fluid with the inner surface of the tank walls, entirely across the tank, 60 each of the compartments 160—162 is preferably divided into further sub-compartments by transverse partitions 170. These sub-compartments, however, are not entirely shut off from one another, since each of said partitions 170 is provided with an aperture as shown, for example, at 172, and preferably disposed at or near the tops of the side walls 150. These apertures are arranged alternately at opposite sides of the tank, or in staggered relation to one another, so as to 65 provide a tortuous path or passage for the flow of the liquid from the inlet pipe 165 to the outlet pipe 166, of each compartment 160—162, as shown clearly in Fig. 20. The liquid entering a pipe 165 will pass downwardly through the adjacent 70

- side of the first sub-compartment, transversely across the bottom thereof, and upwardly through the opposite side thereof, thence longitudinally through an aperture 172 in the adjacent partition 5 170 at that side of the tank, and again downwardly through the adjacent side of the second sub-section, across the bottom thereof and upwardly through the opposite side, and so on back and forth until it is finally discharged through the 10 pipe 166.

By thus dividing the hollow tank walls into several separate compartments, cooling liquid of the desired temperature can be introduced simultaneously into all of these compartments, 15 and by providing the described means for passing the liquid through a tortuous passage in each compartment a very thorough and intimate contact of the cooling liquid with the inner portions of the tank walls will be effected. As a result 20 a substantially uniform cooling action and corresponding rapid exchange of heat between the cooling liquid and the contents of the tank will be made possible.

It will be understood that various changes in 25 the details and arrangements of parts, which have been herein described and illustrated in order to explain the nature of the invention, may be made by those skilled in the art within the principle and scope of the invention, as expressed 30 in the appended claims.

1. Control mechanism for a steeping press of the type in which pulp sheets are steeped in a suitable solution, said press comprising a tank in which the pulp sheets and steeping solution are 35 placed, a platen disposed in said tank and mounted for movement in a direction across the tank to squeeze the pulp sheets and express excess solution therefrom at the end of the steeping operation, hydraulic means for forcing said 40 platen in a pressing stroke, hydraulic means for retracting said platen, and means including a source of operating fluid and a reversible, variable delivery pump connected between said hydraulic means and said source of fluid and forming therewith a hydraulic circuit for causing operation of said platen selectively in opposite directions, said control mechanism including means cooperating with said platen for setting said pump automatically to neutral delivery position at selected points intermediate of the ends of the 50 stroke of the platen in both directions.

2. Control mechanism for a steeping press of the type in which pulp sheets are steeped in a suitable solution, said press comprising a tank 55 in which the pulp sheets and steeping solution are placed, a platen disposed in said tank and mounted for movement in a direction across the tank to squeeze the pulp sheets and express excess solution therefrom at the end of the steeping operation, hydraulic means for forcing said platen in a pressing stroke, hydraulic means for retracting said platen, and means including a source of operating fluid and a reversible, variable delivery pump connected between said hydraulic means and said source of fluid and forming therewith a hydraulic circuit for causing operation of said platen selectively in opposite directions, said control mechanism including means cooperating with said platen for setting said pump automatically to neutral delivery position at selected points between the ends of the stroke in the travel of the platen in both directions, said last named means being adjustable along the direction of travel of said platen, and other means cooperating with said platen at approximately the limits 75

of its stroke in both directions for also setting said pump to neutral delivery and stopping said platen automatically against further travel in either direction.

3. A control mechanism for a steeping press of the type in which pulp sheets are steeped in a suitable solution, said press comprising a tank in which said pulp sheets and solution are placed for steeping, a platen disposed in said tank and mounted for movement in a direction from one 10 upright wall towards the opposite upright wall so as to squeeze the pulp sheets and express excess steeping solution at the end of a steeping operation, and hydraulic means including a reversible flow, variable delivery pump for 15 operating said platen in opposite directions depending upon the direction of delivery of said pump, said control mechanism including a member extending along said tank in the direction of travel of said platen and mounted for 20 movement endwise of itself, means connecting said member to said pump and operable by endwise movement of said member in opposite directions from an intermediate position to reverse said pump, and setting it for neutral 25 delivery when said member is in said intermediate position, a stop adjustably mounted on said member and engageable by said platen at a selected intermediate point in the travel of the platen to move said member in a direction to set the delivery of said pump to neutral delivery and stop operation of said platen, and a latch also carried by said platen for locking said platen to said stop automatically upon engagement therewith, whereby, if the platen overruns its movement and 30 causes a reversal of the pump, said latch will cause a reversible movement of said member with said platen sufficient to reset the pump to neutral delivery and hold it in that position.

4. Control mechanism for a steeping press of 40 the type in which pulp sheets are steeped in a suitable solution, said press comprising a tank in which said pulp sheets and solution are placed for steeping, a platen disposed in said tank and mounted for movement in a direction from one 45 upright wall towards the opposite upright wall so as to squeeze the pulp sheets and express excess steeping solution at the end of a steeping operation, and hydraulic means including a reversible flow, variable delivery pump for operating said platen in opposite directions depending upon the direction of delivery of said pump, said control mechanism including a member extending along said tank in the direction of travel of 50 said platen and mounted for movement endwise of itself, means connecting said member to said pump and operable by endwise movement of said member in opposite directions from an intermediate position to reverse said pump, and setting it for neutral delivery when said member is in 55 said intermediate position, and a stop adjustably mounted on said member and engageable by said platen at a selected intermediate point in the travel of the platen to move said member in a direction to set the delivery of said pump to neutral delivery and stop motion of said platen, one of the cooperating portions of said stop and platen being adjustable into a position in which the platen and stop clear one another upon further movement of the platen in either direction, 60 whereby the stroke of the platen may be resumed and completed after its arrest at said intermediate point.

5. Control mechanism for a steeping press of 70 the type in which pulp sheets are steeped in a 75

- suitable solution, said press comprising a tank in which said pulp sheets and solution are placed for steeping, a platen disposed in said tank and mounted for movement in a direction from one upright wall towards the opposite upright wall so as to squeeze the pulp sheets and express excess steeping solution at the end of a steeping operation, and hydraulic means including a reversible flow, variable delivery pump for operating said platen in opposite directions depending upon the direction of delivery of said pump, said control mechanism including a member extending along said tank in the direction of travel of said platen and mounted for movement endwise of itself, means connecting said member to said pump and operable by endwise movement of said member in opposite directions from an intermediate position to reverse said pump, and setting it for neutral delivery when said member is in said intermediate position, a stop adjustably mounted on said member and engageable by said platen at a selected intermediate point in the travel of the platen to move said member in a direction to set the delivery of said pump to neutral delivery and stop motion of said platen, and relatively fixed stops carried by said member for engagement by said platen as said platen approaches the limits of its movement in both directions to cause a setting of the pump to neutral delivery just before the platen reaches the limits of movement in either direction, said platen and the fixed stop engaged by the platen when the platen reaches its retracted position having interlocking portions for releasably locking the platen and stop together so as to prevent an accidental operation of said member in either direction from neutral delivery position.
6. In a steeping press of the type in which pulp sheets are steeped in a suitable solution, and comprising a tank closed at one end by a gate movable to an open position, a platen disposed in said tank and mounted for movement across the same in a direction toward and from said gate and operable to an extent beyond said gate to eject from said tank pulp sheets disposed vertically in said tank, and hydraulic means including a reversible, variable delivery pump for operating said platen in both directions, the direction depending upon the direction of delivery of said pump and causing no operation of said platen when said pump is in neutral delivery condition, the combination of a control member extending along said tank in the direction in which said platen travels and mounted for endwise movement, means operated by endwise movement of said member for reversing said pump upon reversal of movement of said member and setting said pump to neutral delivery when said member is in an intermediate position, and a stop carried by said member and adjustable endwise along the same, and engageable by said platen at an intermediate point in its travel, whereby further movement of said platen in the same direction will shift said member endwise in the same direction and set said pump to neutral delivery position and stop further movement of the platen in that direction, the engaging portions of said platen and stop being relatively shiftable to clear one another and permit operation of said member in a direction to cause further movement of the platen in the same direction, whereby, when said end gate is opened such further movement may be utilized to eject the pulp sheets from said tank.
7. In a steeping press of the type in which pulp
- sheets are steeped in a suitable solution, and comprising a tank closed at one end by a gate movable to an open position, a platen disposed in said tank and mounted for movement across the same in a direction toward and from said gate and operable to an extent beyond said gate to eject from said tank pulp sheets disposed vertically in said tank, and hydraulic means including a reversible, variable delivery pump for operating said platen in both directions, the direction depending upon the direction of delivery of said pump and causing no operation of said platen when said pump is in neutral delivery condition, the combination of a control member extending along said tank in the direction in which said platen travels and mounted for endwise movement, means operated by endwise movement of said member for reversing said pump upon reversal of movement of said member and setting said pump to neutral delivery when said member is in an intermediate position, and a stop carried by said member and adjustable endwise along the same, and engageable by said platen at an intermediate point in its travel, whereby further movement of said platen in the same direction will shift said member endwise in the same direction and set said pump to neutral delivery position and stop further movement of the platen in that direction, the engaging portions of said platen and stop being relatively shiftable to clear one another and permit operation of said member in a direction to cause further movement of the platen in the same direction, whereby, when said end gate is opened such further movement may be utilized to eject the pulp sheets from said tank.
8. Control mechanism for a steeping press of the type in which pulp sheets are steeped in a suitable solution, said press comprising a tank for the solution and in which the sheets are vertically disposed, a platen disposed in said tank and mounted for movement to and fro in the same, and hydraulic means including a reversible, variable delivery pump for operating said platen in both directions, the direction depending upon the direction of delivery of said pump and causing no operation of said platen when said pump is in neutral delivery condition, said control mechanism including a control member extending along said tank in the direction in which said platen travels and mounted for endwise movement, means operated by endwise movement of said member for reversing said pump upon reversal of movement of said member and setting said pump to neutral delivery when said member is in an intermediate position, a stop carried by said control member and adjustable endwise along the same, an abutting member on said platen which is engageable with said stop at an intermediate point in the travel of said platen to shift said control member and set said pump to neutral delivery position and stop further movement of said platen in the same direction, and a latch carried by said abutment member in a position to hook over said stop and latch said abutment member thereto when said abutment member is in a position to engage said stop, whereby if the overrunning of the platen, when said abut-

ment engages and moves said stop, causes a reversal of the pump, the latch will pull said stop in a reverse direction upon the initial reverse movement of the platen until said member resets said pump to neutral delivery condition.

9. Control mechanism for a steeping press of the type in which pulp sheets are steeped in a suitable solution, said press comprising a tank for the solution and in which the sheets are vertically disposed, a platen disposed in said tank and mounted for movement to and fro in the same, and hydraulic means including a reversible, variable delivery pump for operating said platen in both directions, the direction depending upon the direction of delivery of said pump and causing no operation of said platen when said pump is in neutral delivery condition, said control mechanism including a control member extending along said tank in the direction in which said platen travels and mounted for endwise movement, means operated by endwise movement of said member for reversing said pump upon reversal of movement of said member and setting said pump to neutral delivery when said member is in an intermediate position, a pair of stops carried by said member and adjustable into different positions along the length of the same, an abutment carried by said platen and shiftable thereon into and out of a position in which it will engage and operate either of said stops and, through it, said member in a direction to cause a setting of said pump into neutral delivery condition and stop further operation of said platen in the same direction, and means carried by said abutment and operative when the abutment member is shifted into a position to engage a stop upon movement of the platen to latch said abutment member to that stop upon engagement of the abutment member with that stop, whereby upon any overrunning of the platen that would cause a reversal of the pump, the reverse travel of the platen, through said latch locking said stop to said abutment member, will cause a movement of said member in a reverse direction sufficient to reset said pump to neutral delivery condition.

10. Control mechanism for a steeping press or the like, said press comprising a tank, a platen within the tank and movable across the same, hydraulic means including a variable delivery pumping device for actuating the platen in both directions across said tank, said control mechanism including means operable automatically by said platen at selected intermediate points in its travel across said tank for successively varying the rate of delivery of said pumping device and thereby varying the speed of travel of said platen in corresponding increments during its movement across said tank.

11. Control mechanism for a steeping press or the like, said press comprising a tank, a platen within the tank and movable across the same, hydraulic means including a variable delivery pumping device for actuating the platen in both directions across said tank, said control mechanism including an endwise movable member which by its movement through a predetermined distance in either direction from an intermediate position acts to reverse said pump and set the same for neutral delivery to thereby stop said platen, and

means associated with said member and operable automatically by said platen at a plurality of selected points in its travel across said tank for shifting said member in the same direction a corresponding number of increments of said predetermined distance, whereby the speed of travel of said platen is varied for each increment of movement of said member until the latter has been moved through said predetermined distance and thereby sets said pump in neutral delivery position in which the movement of said platen is stopped.

12. Control mechanism for a steeping press or the like, said press comprising a tank, a platen within the tank and movable across the same, and hydraulic means including a variable delivery pumping device for actuating the platen in both directions across said tank, said control mechanism including an endwise movable member which by its movement through a predetermined distance in either direction from an intermediate position acts to reverse said pump and set the same for neutral delivery to thereby stop said platen, and means associated with said member and operable automatically by said platen while travelling at normal speed to effect a partial movement of said member towards the completion of its movement through said predetermined distance, and other means disposed to be operable by subsequent movements of said platen at successive selected points to effect further increments of movement of said member to complete its travel through said predetermined distance, whereby the speed of the platen is lowered step by step before being stopped by the arrival of said member at the end of its predetermined distance of travel.

13. Control mechanism for a steeping press or the like, said press comprising a tank, a platen within the tank and movable across the same, and hydraulic means including a variable delivery pumping device for actuating the platen in both directions across said tank, said control mechanism including an endwise movable member which by its movement through a predetermined distance in either direction from an intermediate position acts to reverse said pump and set the same for neutral delivery to thereby stop said platen, and means associated with said member and operable automatically by said platen while travelling at normal speed to couple said platen to said member and effect movement of said member towards the completion of its movement through said predetermined distance and thereby reduce the speed of travel of said platen, means for automatically uncoupling said member from said platen before said member reaches the end of its predetermined travel so that said platen may proceed at reduced speed, and other means for likewise coupling said platen to and uncoupling it from said member at subsequent selected points in the continued travel of said platen so that said member is actuated to reduce delivery of said pump and the speed of said platen step by step until said member reaches the end of its predetermined distance of travel, so that said pump is set to neutral delivery position and said platen is thereby stopped.

THOMAS F. STACY.
